DISPENSER FOR TOILET LOTIONS

Morris Fahr, Los Angeles, Calif.
(15831 Vanowen St., Van Nuys, Calif.)

Filed Apr. 8, 1957, Ser. No. 651,285

4 Claims. (Cl. 222—207)

The present invention relates to the general field of dispensers of viscous liquids. It finds particular, although not necessarily exclusive, utility when employed for dispensing lotions, cold cream, and other skin preparations.

A wide variety of dispensers abound in the teachings of the patent literature. By far the majority of these units employ a plurality of machined parts as their basic components. Such construction requires relatively close tolerances and a number of machine operations. In those instances where plastic has been employed, close tolerances are also evident. Such devices, although they may operate satisfactorily, are relatively expensive to manufacture and susceptible of breakdown from clogging and wear.

In this state of the art, the present invention has as its general object to provide a dispenser for viscous liquids which is simple, efficient, and susceptible of economic manufacture from a limited number of plastic parts.

A related and important object of the invention is to furnish a dispenser for viscous liquids which accurately measures out the quantity required in proportion to its manipulation.

Another object of the invention is to provide a dispenser for viscous liquids which, when incorporated in a common cold cream or lotion jar, may be actuated by one hand. A further object of the invention is to provide a dispenser which incorporates self-cleaning features and is a substantial non-fouling construction.

Yet another object of the invention is to provide a dispenser which can be manufactured from a minimum number of moving parts which do not require close tolerances thereby limiting manufacturing costs to an irreducible minimum.

Further objects and advantages of the present invention will become apparent as the following specification proceeds, taken in conjunction with the accompanying descriptive drawings in which:

Figure 1 is a perspective view of a typical lotion bottle fitted with the preferred embodiment dispenser illustrating one application of the present invention.

Figure 2 is a perspective view of the dispenser mechanism which is threaded to the bottle shown in Fig. 1.

Fig. 3 is an exploded perspective view of the dispenser mechanism shown in Fig. 2.

Fig. 4 is a cross section in enlarged scale taken along section line 4—4 of Fig. 1 of the dispenser cap.

Fig. 5 is a sectional view of the dispenser cap assembly taken along section line 4—4 of Fig. 1 showing the dispenser cap assembly in its empty condition.

Fig. 6 is a sectional view of the dispenser cap assembly identical with that of Fig. 5 except that it illustrates the flow of the reservoir contents into the dispenser cap in response to the flexing action as shown in Fig. 5.

Fig. 7 shows the dispenser cap assembly identical with Fig. 5 but illustrating how the contents are discharged through the opening at the top of the cap.

2

Fig. 8 is identical with Fig. 5 except that it shows how the major portion of the contents of the reservoir appears when discharged on to the top of the cap.

Fig. 9 is a perspective view of a cold cream jar incorporating an alternative embodiment of the invention.

Fig. 10 is a partial section in front elevation of the cold cream jar dispenser in its associated jar top shown in the partially broken section.

Fig. 11 is an exploded perspective view in enlarged section of the dispenser construction shown in Fig. 10.

Fig. 12 is a plan view of the plastic disk and associated tube shown at the left portion of Fig. 11.

Fig. 13 is a bottom view of the flexible cap shown at the right central portion of Fig. 11.

Fig. 14 is a sectional view in front elevation of the plastic disk and associated tube shown in Fig. 12 and taken along section 14—14 of Fig. 12.

Fig. 15 is a sectional view in front elevation of the flexible cap shown in Fig. 13 taken along section 15—15 of Fig. 13.

Fig. 16 is an enlarged sectional view in front elevation of the dispenser and associated cold cream jar diagrammatically illustrating the relationship between the cold cream and the dispenser at the time of purchase.

Fig. 17 illustrates the first step in operation of the dispenser as shown in Fig. 9 as the flexible cap is depressed.

Fig. 18 illustrates the second step in operation of the dispenser as the cap is released from the position shown in Fig. 17 illustrating how the cold cream migrates into the cap reservoir.

Fig. 19 illustrates the action of the dispenser in discharging a portion of the contents of the reservoir onto the top of the flexible cap when depressed again in the manner illustrated in Fig. 17.

35 The preferred embodiment of the invention is shown in Fig. 1 as a dispenser cap assembly 10 which is fixed to a lotion bottle 11 or other similar primary reservoir. The dispenser cap assembly, as will be seen in Fig. 2, contemplates a delivery tube which extends down into

40 the contents of the primary reservoir 11, a coupling 14, shown in the form of a modified threaded cap, and a flexible cap 15. Generally the dispenser cap assembly

10 contemplates a check valve assembly at the head of the delivery tube 12 which prevents any back-out of fluid

45 which is pumped into the cap reservoir 16. In addition, the flexible cap 15 is provided with a unique slotted discharge opening or check valve 18. In operation, the user need only repeatedly depress the top 19 of the cap 15 and the contents of the primary reservoir 11 are discharged in measured amounts through the slotted discharge opening 18.

The details of the construction of the preferred embodiment dispenser assembly 10 will be more fully appreciated as their assembled relationship is shown in Fig.

55 3. There it will be seen that the delivery tube 12 is proportioned for a mating fit with the lower extension 20 of the check valve housing 21. A lock ring 22 is provided to secure the check valve body 21 within the threaded coupler 14.

50 A check valve ball 24 is retained within the check valve body 21 by means of a cross pin 25. The flexible cap 15 is coupled to the check valve body 21 by means of the check valve body upper rim 26.

The assembled relationship of the components shown in the exploded form in Fig. 3 is best illustrated in Fig.

55 5. There it will be seen that the upper ring 26 of the check valve body 21 abuts the mounting shoulder 28 provided internally of the flexible cap 15. The lower rim 29 of the flexible cap 15 abuts the flexible cap mounting shoulder 30 provided internally of the threaded cap coupler 14. The lock ring 22 is proportioned to wedgingly secure the check valve body 21 within the threaded

cap 14 where it abuts the internal threads 31 of the threaded cap 14.

A check valve ball seat 32 is provided by a tapered lower portion of the check valve housing 21, and leads directly to the delivery tube mounting extension 29 which in turn is inserted into the delivery tube 12.

Referring now to Fig. 4, it will be seen that the unique discharge opening 18 contemplates a re-enforcing ring 34 at the lower central portion of the flexible top 19 of the cap 15. As shown in Figs. 1 and 2, two crossing 10 slits 35 define four valve flaps 36 which meet at the center of the cap top 19.

The advantages of the construction just described become even more apparent as a typical operational cycle is reviewed as illustrated by Figs. 5 through 8. When the dispenser cap assembly 16 is empty as shown in Fig. 5, the top 19 of the flexible cap 15 is flexed repeatedly by the finger of the user. Each time the cap reservoir 16 is reduced in volume permitting the air to flow out through the opening of the flaps 36. When the finger is released, however, the check valve ball 24 raises sufficiently off its seat 32 in order to incite a pumping action which slowly brings the contents of the primary reservoir 11 up the delivery tube 12. As better seen in Fig. 6, fluid by-passes the check valve 24 and ultimately 25 fills the cap reservoir 16.

Because the hydrostatic pressure required to actuate the upper check valve assembly 18 is less than that required to by-pass the ball check 24, subsequent pumping will release the contents of the reservoir 11 to the top 30 19 of the flexible cap 15 (see Fig. 7). When the pumping has ceased a small portion of the contents of the reservoir 11, for example, hand lotion, appears on the top 19 of the flexible cap 15 as illustrated in Fig. 8. This may be easily wiped off by the user.

In operation it will be appreciated that a wide variety of fluids can be dispensed through the unique dispenser cap. Once the reservoir 16 has been filled, the contents are constantly ready for use. There is no necessity to screw or unscrew a cap from the bottle. In addition, if the reservoir 11 should be knocked over, there is no danger of spill or splatter. The top 19 remains clean because the use of the unique dispenser valve 18 presupposes that the discharged contents will be wiped off in use. As the description of an alternative embodiment of the invention proceeds, it will become apparent that the basic principles of the invention may be applied to a wide variety of physical embodiments.

In broadest outline the alternative embodiment of the invention, to be described hereinafter in greater detail, contemplates a flexible cap with a unique discharge and check valve, a disk which cooperates with the cap to form a reservoir, and the delivery tube coupled with the disk and a second check valve. In operation the dispenser may be attached to a cold cream jar or the like. To actuate the dispenser, the flexible cap is depressed causing a pumping action to take place which delivers the cold cream to the top of the cap in a quantity proportioned to the intensity and frequency of the flexing.

As will be seen from referring to Fig. 9, the dispenser 110 is secured to the top of a cold cream jar 111, the threaded cover 112 of the jar 111 serving as the framework in which the dispenser assembly is mounted. In Fig. 10 it will be seen that threaded cover portion 112 has a central opening into which a flexible cap 114 has been inserted. The delivery assembly 115 extends downwardly into the associated jar 111 in order to pick up its contents.

The details of the construction will be better appreciated after the operational cycle of the dispenser has been reviewed. The stages of operation are illustrated in Figs. 16 through 19. Referring now to Fig. 16, it will be seen that the cold cream 116 or other contents of the jar 111 seeks a relatively level position within the jar. The delivery assembly 115 extends down into the

cold cream 116. When the flexible cap 114 is depressed, as illustrated in Fig. 17, the reservoir area 118 beneath the flexible cap 114 is reduced substantially in size. Upon releasing the flexible cap 114, thereby permitting it to return to its normal position as shown in Fig. 18, the check valve in the delivery tube assembly 115 permits the cream to rise upwardly into the reservoir area 118, in order to satisfy the partial vacuum created after the release. When the flexible cap 114 is again depressed, as shown in Fig. 19, the discharge check valve assembly 119 in the flexible cap permits a portion of the cold cream 146, formerly within the reservoir 118, to be expelled onto the top of the cap, the check valve assembly within the delivery assembly preventing the cream from backing into the jar 111. The more intimate details of the operation of the unit and its theory will become more fully apparent as the details of the various constructional elements are outlined hereinafter.

Referring back to Fig. 11, it will be seen that the delivery assembly 115 contemplates an annular disk 120 and an associated delivery tube 121. The delivery tube 121 has an enlarged collar 122 at the portions where it joins the disk 120 to accommodate an internal check valve. The check valve is made up of a ball 124 which is held in place in the inside of the collar 122 by means of a transverse pin 125. It will be noted that the diameter of the annular disk 120 closely approximates the overall diameter of the flexible cap 114. The cap 114 has a crowned head 113 and a base flange 126, the diameter of the base flange 126 being proportioned to lockingly engage the threads 128 of the jar cover 112.

The details of the delivery assembly are shown in their assembled relationship in Fig. 14. There it will be seen that the annular disk 120 has a hollow central bored portion 129 which receives a cylindrical extension 130 of the collar 122. At the juncture between the cylindrical extension and the collar 122 a diametrical groove is provided in which to secure the check valve retaining pin 125. The check valve ball 124, which may be selected from a standard size bearing ball is proportioned to the remainder of the structure so that in its seated position as shown in Fig. 14 it rests at the mouth of the delivery tube 121. The diameter of the check valve chamber 131 is such that the check valve retaining pin 125 will prevent the check valve 124 from escaping from the check valve chamber after assembly.

The construction of the flexible cap 114 is best illustrated in Fig. 15. There it will be seen that the flexible cap has a peripheral flange 126 and dome-shaped central portion 113 terminating in a support ring portion 132. It will be noted that the outer edge of the support ring 132 tapers downwardly and inwardly along its periphery 134. This taper assists in securing the flexible cap within the opening in the lid 112. The discharge check valve assembly 119 contemplates a downwardly extending ring 135, shown as molded integral with flexible cap 114. Slits 141 are made in the portion of the flexible cap dome 113 which are central to the ring 135. Four such slits 141 defining flaps 145 have been shown intersecting it at the center of dome 113. Although other slitting patterns are contemplated, four are preferable in both operation and manufacture.

Referring again to Fig. 16, it will be seen that in the assembled relationship all of the elements when blended find a unique co-action. The flexible cap 114 and peripheral flange portion 126 serve the two-fold purpose of anchoring the flexible cap 114 to the jar cover 112. The tapered shoulder portion 134 of the flexible cap serves to lock the flexible cap within the cover 112 in the event the cover is removed to insert additional cream into the jar. The delivery tube assembly disk 120 is provided with a peripheral flange portion 142 which abuts sealingly against the jar top ledge 144. An air vent 140 is provided in the form of a notch along the edge of the jar 111.

In review it will be seen that the dispenser of both the preferred and alternative embodiments are made up of a minimum number of elements. Each is relatively inexpensive and easy to mold and assemble with wide dimensional tolerances being allowable. The only moving part is the ball check valve, although the other check valve assemblies may be employed beneath the cap reservoir. Because springs and pistons have been eliminated, the units are insured against the possibilities of sticking, plugging, and corroding. The unique self-closing flap type body valve preserves the moisture content of the fluid in the cap reservoir.

In the event that solutions which require shaking before use are employed, the entire unit can be shaken with the result that the materials in the top reservoir as well as the primary reservoir will be fully mixed before using. The molded nature of the dispenser assembly is inherently lightweight, and consequently will not tend to make the combination with the primary reservoir top heavy. In addition, since the principal part is molded of plastic, a wide variety of colors and decor or shapes may be employed.

Although particular embodiments of the invention have been shown and described in full here, there is no intention to thereby limit the invention to the details of such embodiments. On the contrary, the intention is to cover all modifications, alternative embodiments, usages and equivalents of the dispenser as fall within the spirit and scope of the invention, specification, and appended claims.

I claim as my invention:

1. A dispenser for attachment to a primary reservoir having a threaded top comprising, in combination, a flexible cap characterized by a convex circular top and generally cylindrical side wall portions defining an internal cap reservoir, intersecting slits in the top of the cap defining flaps, a reinforcing ring integral with the cap top and ringing the flap bases, an internal mounting shoulder at the base of the cap side walls, a check valve housing with an upper ring to engage the cap mounting shoulder, a threaded coupler defining a flexible cap receiving opening at its top, a cap lock ring within the coupler which cooperates with the check valve ring to lock the cap in place, a one way check valve within the check valve housing, a lock ring wedgedly securing the check valve housing against upward movement relative to the coupler, and a delivery tube extending into the primary reservoir from the check valve housing which delivers the contents of the primary reservoir into the cap reservoir and through the discharge flaps responsive to the pumping action effected by flexing the cap top.

5 2. A dispenser comprising, in combination, a body defining a central opening, a flexible cap proportioned to fit within said body opening and defining a supply chamber below its top, said cap having a convex circular top with slit flaps therein for discharging the contents of said supply chamber, an internal reinforcing ring integral with said cap top and ringing the bases of said slit flaps, means proportioned to close off the supply chamber defined beneath the flexible cap having a port in its face, a conduit extending downwardly from the supply chamber, a check valve within the conduit, and a lock ring for securing said conduit to said body.

10 3. A dispenser comprising, in combination, a body defining a central opening, a flexible cap proportioned to fit within the body opening and defining a supply chamber below its top, a check valve housing proportioned to close off the supply chamber defined beneath the flexible cap and having a port in its upper portion, a tube extending downwardly from the check valve housing, a ball check valve within the check valve housing, a combination check and delivery valve in the flexible cap characterized by flaps in the cap defined by intersecting slits, an internal reinforcing ring integral with said cap and ringing the bases of said slit flaps, and a lock-ring for securing said check valve housing to said body.

15 4. A dispenser comprising, in combination, a threaded jar lid body defining a central opening, a flexible cap having an offset shoulder proportioned to fit within the body opening and defining a supply chamber below its top, a plate proportioned to close off the supply chamber defined beneath the flexible cap having a port in its face, the plate being proportioned to engage the jar lid threads, a tube extending downwardly from the plate and connecting with the plate port, a check valve within the tube, combination check and delivery valve in the flexible cap characterized by intersecting slits defining discharge flaps, an internal reinforcing ring integral with said cap and ringing the bases of said slit flaps, and a lock-ring for securing said check valve housing to said body.
